FOOTWEAR

Arthur Ingram, London, England, assignor of
one-half to Herbert John Fell, London, Eng-
land

Application February 10, 1939, Serial No. 255,563
In Great Britain February 14, 1938

3 Claims. (Cl. 36—8.5)

This invention relates to boots, shoes, sandals and like articles of footwear. In correct walking the heel should be relieved of pressure and the main weight of the body distributed over the whole of the under-surface of the foot including the great toe and remaining metatarsals. Footwear as at present manufactured does not permit of the foot functioning in this way.

The chief object of the invention is to evolve a construction of boot, shoe or like article of footwear which when worn will result in the direct weight of the body being removed from the ligaments under the astragalus and transferred to the great toe and remaining metatarsals, the foot being thereby allowed to articulate naturally and perform its normal spring function.

A boot, shoe or like article of footwear constructed in accordance with the invention has the under-surface of the forepart of the sole extending from the toe to a point just behind the ball joint and the under-surface of the heel disposed in the same horizontal plane.

That part of the sole immediately beneath the heel or os calcis lies substantially horizontal and substantially parallel with but on a higher level than the forepart of the sole, the arrangement being such that the metatarsals and their associated joints will be located in a horizontal or substantially horizontal plane so as to receive a transference of the weight of the body from the astragalus and leave the cuneiform hinge open to allow the rearward part of the foot behind said hinge to lift in a natural manner and avoid downward pressure and displacement of the centre of the foot. The rearward heel supporting part of the sole thus constitutes a level heel base.

It is preferred that the rearward heel supporting part of the sole shall also lie parallel to the top edge of the quarters and that the inside quarters shall have a "blow" or pocket formed therein extending from just behind the astragalus and terminating in front of the first metatarso-phalangeal joint, so that a close fitting draught can be obtained round the heel, whilst the blow minimizes pressure from the inside quarter on the astragalus, navicular, internal cuneiform, first metatarsal and great toe joint.

In order that the said invention may be clearly understood and readily carried into effect, the same will now be more fully described with reference to the accompanying drawings, wherein:

Figure 1 is a side elevation of a last for use

in the construction of an article of footwear in accordance with the invention.

Figure 2 is a plan view of same.

Figure 3 is a front elevation.

Figure 4 is a rear elevation.

Figures 5 to 10 are sections respectively on the lines 5—5 to 10—10 in Figure 1.

The last illustrated includes a forward portion 20 extending from the toe to just behind the ball joint and an elevated heel portion 21 10; constituting a level heel base, the parts 20 and 21 lying parallel or substantially parallel with one another. The last is shown fitted with a heel 22 the under-surface of said heel and the under-surface of the forepart 20 of the sole lying in the same horizontal plane.

The dotted line 23 represents substantially the upper edge of the quarters and the dotted line 24 a line joining the centre 25 of the back seam, with the centre 26 of the throat. The line 24 20 if continued as shown in Figure 2 passes through that part of the toe of the shoe which accommodates the third metatarsal.

The last from a point just behind the astragalus and terminating in front of the first metatarso-phalangeal joint is formed with an outwardly projecting protuberance 27 (see Figures 3, 4, 6, 9 and 10) for entering a correspondingly shaped "blow" or pocket in the upper of the finished shoe, for minimizing pressure from the inside quarter on the astragalus, navicular, internal cuneiform, first metatarsal and great toe joint, a close fitting draught being obtained round the heel.

The last is formed with a concavity 28 (see 35 Figures 6 and 9) in its under-surface, for producing a corresponding upstanding convex portion in the finished shoe immediately behind the muscles, i. e. transverse pedis, lying beneath the cuneiform and metatarsal joints.

The outside form is draughted in tightly round the heel, under the ankle, over the cuboid and metatarsals, across the phalanges and terminating on the inner side over the first phalanx of the great toe, the rear portion of the outside form extending tightly round the heel and under the ankle constituting with the counterpart of the inside form a bandage to assist in the retention of the rear part of the foot in correct position, the remaining or forward part of the outside form constituting a strap to hold down the portion of the foot over which it passes including the first phalanx of the great toe, to ensure the great toe being in position to take a trans-

ference of weight from the astragalus, thus ensuring natural movement.

In forming a last according to the invention the patient is stood upright on a horizontal surface and the shape of the foot in plan thus obtained. The block of wood from which the last is to be constructed is then taken, the horizontal under-surface of the wood being taken as the theoretical heel base. The forward or sole part 10 of the last is then built up by adding material to the forward under-surface of the last until the sole portion lies below the heel base to the requisite degree, the under-surface of the forward sole portion lying in a plane substantially 15 parallel to the heel base but at a lower level and in the same horizontal plane as the under-surface of the heel used in the finished shoe.

Preferably, in the construction of a boot or shoe in accordance with the invention, the inside 20 quarter is shaped with its top line cut downwardly towards the back seam edge, the upper point of the back seam edge of the inside quarter being below, conveniently about $\frac{3}{4}$ ", the corresponding point of the outside quarter, so that 25 when this edge is seamed to the corresponding back seam edge of the outside quarter, the inside quarter has first to be lifted to align the said edges whereby a pocket or blow will be formed. In forming the vamp, the inside wing 30 of the vamp is down so that to seam the said wing to the quarter seam the said wing has first to be lifted so as to centralize the vamp and form a forward continuation of said blow in the inside quarter, the said blow including the forward continuation 35 extending from just behind the astragalus and terminating in front of the first metatarso-phalangeal joint, the arrangement being such as to give a close fitting draught around the heel and by reason of the blow minimize pressure from the inside quarter on the astragalus, navicular, internal cuneiform, first metatarsal and great toe joint and also to give a tight draught across the phalanges to retain the toes and joints in a horizontal plane.

Footwear constructed in accordance with this 40 invention is preferably provided with a metal shank secured to the under-surface of the inner sole and extending from the joints to a point just behind, conveniently about $\frac{1}{2}$ ", in front of the heel. The shank is formed with a transverse 45 convex upper surface beneath the second, third and fourth metatarsal heads, so that the inner sole beneath such head has a transverse concavity constituting an anterior metatarsal support.

A heel for use with footwear constructed in accordance with this invention is formed with the

surface of the base parallel or substantially parallel with the surface of the top piece so that the heel is devoid of pitch.

What I claim and desire to secure by Letters Patent of the United States is:

1. An article of footwear having the under-surface of the forepart of the sole extending from the toe to a point just behind the ball joint and the under-surface of the heel disposed in the same horizontal plane, the part of the sole immediately beneath the os calcis lying substantially horizontal and substantially parallel with but on a higher level than the forepart of the sole, the upper edge of the quarters being so cut that a line joining the upper edge of the back seam 10 to the upper forward edge of the quarters lies substantially parallel with the heel supporting part of the sole.

2. An article of footwear having the under-surface of the forepart of the sole extending from 20 the toe to a point just behind the ball joint and the under-surface of the heel disposed in the same horizontal plane, the part of the sole immediately beneath the os calcis lying substantially horizontal and substantially parallel with but on a higher level than the forepart of the sole, the upper edge of the quarters being so cut that a line joining the upper edge of the back seam 25 to the upper forward edge of the quarters lies substantially parallel with the heel supporting part of the sole, the inside quarters being formed with a "blow" extending from just behind the astragalus and terminating in front of the first metatarso-phalangeal joint.

3. An article of footwear having the under-surface of the forepart of the sole extending from the toe to a point just behind the ball joint and the under-surface of the heel disposed in the same horizontal plane, the part of the sole immediately beneath the os calcis lying substantially horizontal and substantially parallel with but on a higher level than the forepart of the sole, the upper edge of the quarters being so cut that a line joining the upper edge of the back seam to the upper forward edge of the quarters 40 lies substantially parallel with the heel supporting part of the sole, the inside quarters being formed with a "blow" extending from just behind the astragalus and terminating in front of the first metatarso-phalangeal joint, a vertical plane 45 extending from the centre of the upper edge of the back seam through the centre of the throat passing through that part of the toe of the article of footwear in which the third metatarsal is accommodated.

ARTHUR INGRAM.
